UNITED STATES PATENT OFFICE.

HERMANN M. HIRSCHBERG, OF NEW YORK, N. Y.

DESIGN FOR A GLOBE FOR ARC-LAMPS.

42,941.

Specification for Design.

Patented Aug. 27, 1912.

Application filed May 23, 1912. Serial No. 699,331. Term of patent 7 years.

To all whom it may concern:

Be it known that I, HERMANN M. HIRSCHBERG, a subject of Great Britain, residing at the city of New York, borough of Manhattan, county and State of New York, have invented a new, original, and ornamental Design for a Globe for Arc-Lamps, of which the following is a specification, reference being had to the accompanying drawing, forming a part thereof.

Figure 1 is an elevation of an arc lamp globe, showing my design, and Fig. 2 is a plan view of the same.

I claim—

The ornamental design for a globe for arc lamps, as shown.

HERMANN M. HIRSCHBERG.

Witnesses:

H. L. AMDURY,
J. J. FEELEY.
